UNITED STATES PATENT OFFICE.

GIOVANNI FRANCHINI AND CARLO BARTOLOMEE, OF SAN FRANCISCO, CALIFORNIA.
RELEASING DEVICE.

1,228,360.

Specification of Letters Patent.

Patented May 29, 1917.

Application filed July 18, 1916. Serial No. 109,944.

To all whom it may concern:

Be it known that we, GIOVANNI FRANCHINI, a subject of the King of Italy, and CARLO BARTOLOMEE, a citizen of the United States, residing in the city and county of San Francisco and State of California, have invented new and useful Improvements in Releasing Devices, of which the following is a specification.

10 This invention relates to an animal releasing device.

One of the objects of the present invention is to provide a simple, substantial, cheaply manufactured, easily operated releasing device whereby the halter ropes attached to horses or cattle in one or more stalls may be simultaneously released. Further objects will hereinafter appear.

The invention consists of the parts and 20 the construction and combination of parts as hereinafter more fully described and claimed, having reference to the accompanying drawings, in which—

25 Figure 1 is a front elevation, partly broken away, of the releasing device.

Fig. 2 is a cross section on line 2—2 of Fig. 1.

30 Fig. 3 is a cross section on line 3—3 of Fig. 1.

Fig. 4 is a front elevation of a number of stalls, showing the application of the invention.

Referring in detail to the drawings, A indicates a suitably shaped casing, provided 35 at one end with a pair of upwardly extending lugs 2 and 3 and at the other end with an upwardly extending lug 4. Slidably mounted in the casing and having its larger end extending through the lug 4 is a bolt 5, the 40 other end of which is slightly reduced in diameter and is sufficiently long to extend through the lugs 2 and 3. Secured upon the enlarged end of the bolt is a nut or adjusting collar 6, between which and lug 4 is 45 interposed a coil spring 7. This spring is provided for the purpose of normally holding the bolt in the position shown in Fig. 1 known as locked position.

Formed on the casing A and integral 50 with lug 4 is a pair of bracing ribs 8, arranged one on each side of the bolt, and also formed integral with lug 2 is a bracing rib 9. The rib 9 not only forms a brace for the lug 2 but also an extension or guide for the reduced end of the bolt 5. It, furthermore, serves as a support for one end of a cover

10, the opposite end of which is supported by the ribs 8 and is secured in position by screws 11.

The cover 10 is just sufficiently long to pass 60 between the lugs 2 and 4 and in this manner inclosing the bolt, with attached collar 6 and surrounding spring 7. Positioned between the lugs 2 and 3 and supported by the reduced end 12 of the bolt 5 is a keeper 14. 65 This keeper is perforated at its upper end to permit the reduced end of the bolt to pass through, and is, furthermore, provided with a perforated extension 15 adapted to receive a ring 16 to which a halter rope may be 70 tied or otherwise secured. The keeper, with attached ring and halter rope, may be released by retracting the bolt or moving it in the direction of arrow a sufficiently far to pull the bolt out of the keeper. The 75 keeper thus released will drop down and the halter rope is consequently released leaving the animal free to leave the stall.

A releasing device constructed as here shown may be installed, one in each stall, 80 such as shown in Fig. 4, and for the purpose of permitting all the halter ropes to be released simultaneously a rod or flexible cable 17 has been provided. This passes through the stalls and is preferably attached to a 85 spring 18 at one end and to a lever 19 at the other end. Forming a connection between each bolt 5 and the cable 17 is a bracket formed with a clamp 20, at its upper edge and also formed with a downwardly directed, perforated extension 21. This extension permits a connection to be made between the bolt and the cable as it is only necessary to connect the two by means of a link or flexible cable 22; the cable 22 being, preferably, provided as it permits each individual releasing device to be operated without affecting the others. 95

In operation, with the keepers in position between the lugs 2 and 3 and the provision 100 of the cable 17 and the connections formed between same and each individual bolt 5, if it is desired to release all the halter ropes simultaneously it will only be necessary to pull the lever 19 in the direction of arrow b. 105 Movement of the cable 17 in the same direction will thus retract all the bolts simultaneously and release the keepers 14, with attached rings and halter ropes. The advantage of this can readily be appreciated if 110 fire or other accidents should occur, as it permits all the animals to be released at once,

2
thus giving them a chance to escape from the stable.

The structure, furthermore, permits each individual bolt to be retracted, if it is desired to release one animal at a time, as it is only necessary to grasp the head 23 of any bolt 5 and pull it in the direction of arrow a. The provision of the cable 22, between the clamp and the bolt, permits any individual bolt to be retracted without affecting the others. It is thus possible to release animals singly or severally. While two stalls are here shown, it is obvious that any number may be connected and equipped as shown, and that while a lever 19 has been provided for the purpose of moving the cable, it is obvious that this may be automatically operated by an electric control or in any other manner desired.

20 The device as a whole is substantial in construction and is so cheaply manufactured that it may be installed by practically any one, and is so simple in construction that it will never get out of order.

25 The materials and finish of the several parts of the device are such as the experience and judgment of the manufacturer may dictate.

We wish it understood that various 30 changes in form, proportions and minor details of construction may be resorted to within the scope of the appended claim and

Copies of this patent may be obtained for five cents each, by addressing the "Commissioner of Patents, Washington, D. C."

that we do not wish to limit ourselves to the specific design and construction here shown.

Having thus described our invention, what we claim and desire to secure by Letters Patent is—

In a releasing device, a casing having compartments, a spring pressed bolt operating in the casing and having an eye extending beyond an end of the casing, a flexible cable positioned above the top of the casing, a bracket member having a substantially wide upper end doubled upon itself to form an eye and having its terminal seated on one of the faces of said member, said bracket eye receiving the flexible cable, screws passed through the eye terminal and body of the bracket member, the lower end of the bracket extending downwardly and having a perforation disposed at a point in the same horizontal plane with the bolt, a flexible cable secured in the perforation of the bracket and in the eye of the bolt, and a keeper in one of the compartments having an opening adapted to receive the other end of the bolt.

In testimony whereof we have hereunto set our hands in the presence of two subscribing witnesses.

GIOVANNI FRANCHINI.
CARLO BARTOLOMEE.
